UNITED STATES PATENT OFFICE.

CHARLES BROOKE JONES, OF ABOVE CYNWYD, PENNSYLVANIA.

FUSE PLUG AND SOCKET.

Application filed March 29, 1921. Serial No. 456,599.

My invention relates to fuses for electric circuits.

The purpose is to provide a fuse having a cylindrical barrel which will be of different diameters according to the capacity of the fuse.

A further purpose is to form the contacts entirely beneath the barrel and to connect the plug with the socket by a partial turn 10 only.

A further purpose is to accommodate the fuse and socket or fuse block to the insertion of but one size fuse within a given socket.

A further purpose is to provide an insulating fuse socket free from other contacts than holding mechanism and to retain the fuse in position by the contacts.

A further purpose is to form laterally projecting contact members at the lower end of 20 a fuse and engage them with cooperating contact devices beneath the fuse socket and acting as retaining devices only.

A further purpose is to locate a fuse block adapted for retention by the contact devices, 25 so that it will turn in the direction of engagement only.

Further purposes will appear in the specification and in the claims.

I have preferred to illustrate my invention 30 by but one general form, selecting a form which is practical, efficient, thoroughly reliable and relatively inexpensive and which at the same time well illustrates the principles of my invention.

Figure 1 is a perspective of the preferred 35 form of a plug and socket embodying my invention in assembled position.

Figure 2 is a top plan view of the structure seen in Figure 1.

Figure 3 is a section upon line 3-3 of 40 Figure 4, showing a bottom plan view of part of the structure.

Figure 4 is a section upon line 4-4 of Figure 3.

Figures 5 and 6 are sections upon lines 45 5-5 and 6-6 of Figure 2.

Figure 7 is a section upon line 7-7 of Figure 3.

Figure 8 is a central vertical section in 50 perspective of the fuse plug seen in the other figures.

Figure 9 is a section corresponding to Figure 4 showing a fuse plug and socket of the same type but of different capacity.

In the drawing similar numerals indicate 55 like parts.

All of those familiar with existing commercial incandescent light and small capacity power circuits recognize the objection to interchangeable fuses whereby a fuse of almost any capacity may be inserted within a circuit which has been designed and wired for a low current only.

For example, house circuits designed to carry a very low current only, too frequently 65 carry as high a current as the main house fuses will stand, because of a shift in fuses made by the householder without consulting the electrician or any authorities who should control. My invention has been directed in part to prevention of such interchanging of fuses and in the hope that cooperation with the underwriters with respect to a new fuse will make it possible to prevent 70 such substitution of improper sizes of fuses. 75 However, most of the features of my invention are suitable for fuse work generally, whether the distinction between different sizes of fuses be maintained or not.

My fuse construction contemplates a special fuse socket member 10 and cooperating fuse plug 11. The socket member comprises an upper block 12 and a cover plate 13. The block consists of a relatively flat body member 14 and an upwardly extending cylindrical shell 15. The body is recessed toward the ends from the middle to form a space 16, between it and the protecting plate, which space is bounded by the wall 17. The interior of the block forms a barrel for the plug, 80 presenting an interior cylindrical surface 18. This barrel is axially grooved at the sides to form slots 19 and 20 which bottom at 21 and 22.

Two pairs of contacts 23, 23' and 24, 24' 85 are located one pair at each end or side of the plug. They are bent to a general Z shape in order to facilitate their anchorage within the block. These contacts are passed through or cast into the porcelain or other 90 insulating material of the blocks and their actual engaging portions are in the form of mating pairs of wiping plates 25, 25' and 26'.

At their upper ends these contacts extend 105 transversely as seen at 27 and 28 across the exposed, preferably depressed upper surface 29 of the base as best seen in Figure 1,

and are held in position by screws 30 inserted from the bottom to avoid interference with or accidental release of the contacts. Binding screws 31 also connect the plates and 5 pass through openings 32 in the blocks.

The lower of the wiping plates should be of spring metal and the two of the pair should be separated at the ends to provide for insertion of the contacts carried by the 10 plug. I find that it is desirable to recess the under-side of the block additionally at 33, 34 to provide spaces for movement of the plug contacts, and to still further recess the block at 35 for the upper plates, so that the 15 lower faces of the upper contact plates shall be level with the bottom of the recesses 33, 34 which will then guide the plug contacts between the pairs of wiping contact plates.

The block 12 and cover plate 13 are held 20 together by bolts passing through the openings 36 and inserted from the top.

Both the cover or facing plate 13 and the block are held to the support by bolts 37 passing downwardly through them.

25 Within the socket thus provided I apply the plug 11 having a barrel structure corresponding generally to the interior barrel of the socket. The contact members 38, 39 are preferably cast within it, with portions 40 and 41 embedded in the porcelain and with their upper portions turned toward each other as at 42 within a recess 43 so that the fuse 44 may be secured across them.

The upper end of the plug is flanged at 45 25 and carries an annular, preferably knurled ring 46 by which the mica cover 47 is held in place. The plug is extended axially at the bottom at 48, so as to rest upon the plate 13 to form a stop, in such position that the 40 laterally projecting ends or fingers 49, 50 of contact members 38, 39 wipe contact pairs 25, 25' and 26, 26' when the block is given a partial turn. Though the block is free to turn to the left in Figure 3 (to the right in 45 Figure 1) to cause engagement of the parts, it is not free to turn in the reverse direction because of flanges 51 which form stops to prevent reverse movement of fingers 49 and 50.

50 I prefer to make the sockets of standard external size, the same for a considerable range of fuse sizes, but to make the bores at 18 different for different sizes, so that a smaller fuse, for example, such as shown in 55 Figure 9 shall have a smaller bore 18' in its socket and a smaller diameter plug, to prevent replacement by a larger fuse. The distance between the fingers 49 on one side and 50 on the opposite side is preferably 60 varied with the size of bore, so as not to require an excessive projection of the fingers for the larger sizes.

It will be obvious that my disclosure herein will suggest other forms than those here 65 illustrated and that the skill of those work-

ing in the art as well as the whim or preference of the designer and the particular needs he has in mind will result in many changes. I purpose including herein all such as fall within the reasonable spirit and 70 scope of my invention.

Having thus described my invention, what I claim as new and desire to secure by Letters Patent is:—

1. In a fuse plug and socket, the combination of a base having a bore and grooves in communication with the bore, the base being recessed about the bore, contacts within the base at a greater distance from the center than the bore and passing through the base, 75 binding posts on the upper side of the base engaging said contacts, a plug having a diameter corresponding to the bore, contacts carried by the plug adapted to fit within the grooves and engage with the first named contacts and a stop limiting the insertion of the plug to bring the contacts in line for engagement.

2. In a fuse plug and socket, a socket having a bore and an upper member recessed in 90 the lower portion, a closing plate attached thereto, a pair of horizontally extending contact fingers on each side of the socket within the recess, a plug adapted to fit the bore, contacts thereon extending laterally at their 95 outer ends at its lower end and at their inner ends upwardly therefrom within the plug to a recess in the plug and a fuse joining the upper ends of the contacts.

3. In a fuse plug and socket, a body having an upper member recessed in the lower portion, a closing plate attached thereto to form a bottom, a pair of horizontally extending contact fingers on each side of the fuse body within the recess, a plug adapted to fit 105 the bore and its end bottoming on the closing plate, contacts extending horizontally therefrom within the plug to a recess in the plug and a fuse joining the upper ends of the contacts.

4. A fuse plug comprising approximately cylindrical sides having a recess in the upper portion, a transparent closure for said recess, contacts embedded in the plug, extending laterally from the lower parts of the 115 sides and upwardly within the body of the plug and terminating in the recess and a fuse joining the upper ends of the contacts.

5. A fuse socket comprising an upper member having a bore, grooves in communication with the bore, recessed in the lower part and additionally recessed in one direction of plug rotation adjacent the grooves, affording a stop against plug rotation in the opposite direction, contacts lying within the 120 additionally recessed portion, binding posts connected with said contacts, accessible upon the upper surface of the socket and a closure plate for said recess in the lower part of the 125 socket.

6. A socket body having a bore and a recess in the lower part of the body and grooved in communication therewith, a pair of contact plates extending along the surface of the body, passing downwardly through the body and extending into the recess, adjacent the bore, a retaining screw for said plates accessible from within the recess and holding the plates together outside the body, a binding post engaging one of the plates and a closure for the bottom recess. 50
- 5 7. In a fuse socket, a body portion having a bore and grooves in communication with the bore and having a recess in the bottom and an additional recess communicating therewith adjacent the grooves in one direction of plug rotation and affording a stop in the opposite direction thereof, a pair of contact plates in each additional recess extending upwardly through the body and terminating above the body and a closure for the bottom recess. 60
- 10 8. In a fuse plug and socket, a fuse plug having a straight cylindrical body, a fuse within a recess in the upper part of the body and contact strips connected with the ends of the fuse, tightly embedded in the material of the body and extending laterally from the body and a socket having a bore corresponding to the cylindrical plug and grooved adjacent thereto for entry of the contacts, in combination with cooperating contacts within the socket. 65
- 15 9. In a fuse plug and socket, a fuse plug having a straight cylindrical body, a fuse within a recess in the upper part of the body and contact strips connected with the ends of the fuse, tightly embedded in the material of the body and extending laterally from the body and a socket having a bore corresponding to the cylindrical plug and grooved adjacent thereto for entry of the contacts, in combination with cooperating contacts within the socket. 70
- 20 10. In a fuse plug and socket, a fuse plug having a straight cylindrical body, a fuse within a recess in the upper part of the body and contact strips connected with the ends of the fuse, tightly embedded in the material of the body and extending laterally from the body and a socket having a bore corresponding to the cylindrical plug and grooved adjacent thereto for entry of the contacts, in combination with cooperating contacts within the socket. 75
- 25 11. In a fuse plug and socket, a fuse plug having a straight cylindrical body, laterally extending contacts near the bottom of the body and a projection below the contacts, in combination with a socket having a bore corresponding to the body, laterally grooved adjacent the bore and extending below the bottom of the bore, contacts adapted to be engaged by the contacts of the plug and a bottom closure acting as a stop to the said projection. 80
- 30 12. A fuse socket having a longitudinal bore grooved at the sides and a counterbore at one end thereof, vertically spaced pairs of contacts on opposite sides of the bore in the counterbore affording wiping contact and plug for the socket having laterally extending contacts adapted to pass into the space between the contacts of the bores into wiping engagement with them. 85
- 35 13. A socket having a longitudinally grooved bore and a counterbore at one end thereof, a pair of vertically spaced engaging contact strips on each side entering the counterbore and extending outside of the socket for electrical connection therewith, a fuse plug fitting the bore, a fuse within the plug and contacts connected with the fuse within the plug and extending longitudinally of the plug and then laterally thereto and adapted to engage the contact within the bores. 90
- 40 45 50 55 60 65 70 75 80 85 90
10. In a fuse plug and socket, a fuse plug
